HARRY A. SHAW, OF EAST LANSING, MICHIGAN, ASSIGNOR TO REO MOTOR CAR COMPANY, OF LANSING, MICHIGAN, A CORPORATION OF MICHIGAN

DESIGN FOR A RADIATOR SHELL FOR AUTOMOBILES

Application filed May 4, 1931. Serial No. 39,707. Term of patent 7 years.

To all whom it may concern:

Be it known that I, HARRY A. SHAW, a citizen of the United States, residing in East Lansing, in the county of Ingham and State of Michigan, have invented a new, original, and ornamental Design for Radiator Shells, of which the following is a specification, reference being had to the accompanying drawings, forming a part thereof, wherein.

Fig. 1 is a front elevational view of a radiator shell designed according to my invention;

Fig. 2 is a side elevational view of the construction shown by Fig. 1;

Fig. 3 is a plan view of the construction shown by Fig. 1;

Fig. 4 is a cross-sectional view, on a larger scale, taken substantially along line 4—4 of Fig. 1;

Fig. 5 is a cross-sectional view on a larger scale taken substantially along line 5—5 of Fig. 1;

I claim:

The ornamental design for a radiator shell for automobiles, as shown.

HARRY A. SHAW.
